JAMES BERG AND GUSTAV BERG, OF BROOKLYN, NEW YORK.

HYDROMETER.

1,179,996

Specification of Letters Patent.

Patented Apr. 18, 1916.

Application filed July 31, 1915. Serial No. 42,910.

To all whom it may concern:

Be it known that we, JAMES BERG and GUSTAV BERG, citizens of the United States, and residents of Brooklyn, in the county of 5 Kings and State of New York, have invented certain new and useful Improvements in Hydrometers, of which the following is a specification.

This invention relates to hydrometers and 10 more especially to syringes in which the hydrometers are contained and operated, and the object of the invention is to provide a transparent tube with a bulb at the point where the scale of the hydrometer is read 15 and having a flexible bulb at the upper end and a flexible nozzle at its lower end, with various other details of construction, whose objects will be more fully described in the following specification, set forth in the 20 claims and illustrated in the accompanying drawings, wherein:

Figure 1. is a side elevation of the device. Fig. 2. is a vertical sectional view of the same. Fig. 3. is a plan view of the tube 25 with the flexible bulb removed. Fig. 4. is a view of the tube with the other parts detached. Fig. 5. is a plan view of the nozzle.

The present invention is designed to overcome serious objections in hydrometer syringes as heretofore made, and where the instrument is read with difficulty and the latter was liable to be carried up within the flexible bulb used to fill the tube of the syringe, or to close the outlet of the nozzle when 35 the said bulb was compressed to expel the air.

In order to provide freedom of movement for the hydrometer so that it can be read, the tube 10 of the syringe is enlarged into a 40 bulb 11 near its upper end, or at the point where it is generally read, in order that the instrument may float freely and not hug one side of the tube, rendering accurate reading difficult. With the scale of the hydrometer extending into the bulb while its 45 enlarged lower end is located in the tube, the scale is read with more ease as it can be relied upon to occupy a central point equidistant from the sides of the bulb where it 50 will not be distorted by the convexity of the said bulb. The upper end of the tube is provided with a flange 12 on which is fitted the flexible bulb 13 and of such size that when the air is expelled from the tube a sufficient

amount of liquid returns to fill the empty 55 tube to a point where the hydrometer may be conveniently floated. Within this end of the tube is located a perforated washer 14 which permits the air to freely pass into and out of the flexible bulb, but prevents the hydrometer from passing out of the tube and 60 into the bulb. The lower end of the tube 10 is reduced as at 15 and into this end is fitted the head 16 of the nozzle 17. This nozzle is hollow throughout its length and the inner 65 end of the head is tapered and provided with ribs 18, so that when the weighted bulb 19 of the hydrometer descends as the liquid is expelled, it will rest on the ribs and not close the outlet of the nozzle. The ribs will support the bulb 19 at such a distance as to let 70 the liquid pass out.

The construction above described provides a simple and cheap device for accomplishing the results desired and the nozzle, tube and 75 flexible bulb are readily assembled or separated for repairs or shipping. Any one of the parts if lost or injured may be replaced at a small cost.

It is obvious that the parts may be modified or altered without departing from the essential features above described nor from the scope of the appended claims.

What we claim as new, is:

1. In hydrometers, the combination with 85 a transparent tube having a bulb near one end, of a filling bulb at one end, a flexible nozzle at the other end with a ribbed head fitting into the tube and a hydrometer within the tube.

2. In hydrometers, the combination with 90 a transparent tube, of a hydrometer within the same, a bulb in the tube substantially at a point where the scale of the hydrometer is to be read and adapted to facilitate the 95 reading of the scale, a flexible nozzle at the lower end of the tube and having a ribbed upper end, a washer at the upper end of the tube, and a filling bulb at the same end of the tube.

Signed at Brooklyn in the county of Kings and State of New York this 26 day of March A. D. 1915.

JAMES BERG.
GUSTAV BERG.
